TRANSFORMER WITH TWO-PART CORE FOR FLUORESCENT LAMP CIRCUITS
Donald Frederick Chapman, London, England, assignor to Thorn Electrical Industries Limited, London, England
Filed June 9, 1965, Ser. No. 462,638
2 Claims. (Cl. 315—278)

ABSTRACT OF THE DISCLOSURE

A circuit arrangement of the semi-resonant start type for electric discharge lamps has primary and secondary windings which each include two coils connected in series and each of the four coils of the windings is wound around a different one of the limbs of the two U-shaped core parts which are arranged to form a magnetic circuit with air gaps between the ends of the limbs. The two primary coils may be wound around the limbs of one of the U-shaped core parts and the two secondary coils around the limbs of the other or the primary and secondary coils may be arranged in alternation around the magnetic circuit. The leakage reactances can easily be adjusted by altering the air gaps between the U-shaped core parts.

The present invention relates to circuit arrangements of the semi-resonant start type for electric discharge lamps such as fluorescent tubes.

This type of circuit arrangement has a primary winding in the supply circuit of the lamp and a secondary winding and a capacitor in series forming a starting circuit which, with the lamp in position, is connected to the supply circuit through the electrodes of the lamp, the primary and secondary windings being connected in opposition and magnetically coupled.

FIGURE 1 of the accompanying drawings shows such a circuit and FIGURES 2 and 3 show the equivalent circuits under starting and running conditions, respectively.

In FIGURE 1 the A.C. mains supply is applied across supply terminals 10 and 11. The circuit includes primary and secondary windings each of which is divided into two coils for reasons to be explained below. The coils P1 and P2 of the primary winding are connected in series in the supply circuit between the supply terminal 10 and one side of an electrode filament 12 at one end of a fluorescent lamp 13. The coils S1 and S2 of the secondary windings are connected in series with a capacitor C between the other side of the electrode filament 12 and one side of an electrode filament 14 at the other end of the lamp 13, the other side of the electrode filament 14 being connected to the supply terminal 11. The primary and secondary windings are coupled by a magnetic core on which they are wound and, as indicated by the arrows in FIGURE 1, are connected in opposition.

In FIGURE 2 the opposing reactances of the primary and secondary windings are represented by XP and XS and the leakage reactances by X_p and X_s . During starting current at first flows only in the circuit from terminal 10 through X_p and XP, through electrode filament 12, through XS, X_s and C, and through electrode filament 14 to the terminal 11. The opposed reactances XP and XS cancel and with appropriate values for the other elements

2

a starting voltage is developed across X_s and C which is greater than the voltage applied to the terminals 10 and 11. The current flowing in this circuit heats the electrode filaments to the electron-emissive temperature and the lamp starts under the influence of the applied starting voltage.

The currents through XP and XS are now no longer equal but these reactances can be replaced by a mutual reactance XM through which the lamp current flows, as shown in FIGURE 3. The leakage reactances X_p and X_s now serve, under running conditions, to limit harmonic frequencies generated by the lamp being fed back into the supply. To achieve the best results it is desirable to be able to adjust these leakage reactances when assembling the ballast unit formed by the two windings and the magnetic core. The invention provides a novel construction which enables this to be achieved in a simple manner.

In accordance with the invention a circuit arrangement of the semi-resonant start type for electric discharge lamps has primary and secondary windings which each include two coils connected in series and each of the four coils of the windings is wound around a different one of the limbs of the two U-shaped core parts which are arranged to form a magnetic circuit with air gaps between the ends of the limbs.

The two primary coils may be wound around the limbs of one of the U-shaped core parts and the two secondary coils around the limbs of the other or the primary and secondary coils may be arranged in alternation around the magnetic circuit.

The leakage reactances can easily be adjusted by altering the air gaps between the U-shaped core parts.

The construction of the ballast unit in one example of a circuit arrangement in accordance with the invention will now be described with reference to FIGURE 4 of the accompanying drawings, which shows the ballast unit diagrammatically.

The coils P1 and P2 of the primary winding are wound around the limbs of a laminated U-shaped core part 15 of rectangular cross-section. The coils S1 and S2 of the secondary winding are wound around the limbs of a similar U-shaped core part 16. The four coils are identical coils wound from enamelled copper wire interleaved with paper. To simplify winding the coils P1 and S1 are wound on a common former fitting closely over the limbs of the two core parts 15 and 16 and the coils P2 and S2 are wound on a second former. The core parts with the coils are fitted in a sheet steel case of known type with the air gaps between the ends of limbs of the core parts set to give the desired reactances and are embedded in a potting resin in known manner.

For a 65-watt lamp operating on a 240 volt 50 c./s. supply the total reactance of the primary winding was 320 ohms and that of the secondary winding the same. The leakage reactance of the primary and secondary windings combined in opposition was 140 ohms. This ballast unit was used with a capacitor having a capacitance of 6.0 mfd. The total harmonic content detected in the supply current waveform was less than 3%.

When smaller leakage reactances are required the coils P2 and S2 may be interchanged, the coils P1 and P2 remaining connected in series and in opposition to the coils S1 and S2.

I claim:

1. A circuit arrangement of the semi-resonant start type for an electric discharge lamp, said circuit comprising primary windings in series with the lamp and secondary windings in shunt with the lamp each including two coils connected in series and further comprising two U-shaped core parts having limbs around which said coils are wound, said core parts being arranged to form a magnetic circuit with air gaps between the ends of the said limbs, and each of the four coils of said windings being wound around a different one of the said limbs.

2. A circuit arrangement as claimed in claim 1 in which the primary coils are wound around the limbs of one core

5 part and the secondary coils around the limbs of the other core part.
